UNITED STATES PATENT OFFICE.

HARRY G. HALL, OF ATLANTA, GEORGIA.

PASTEBOARD TRAY.

1,271,033.

Specification of Letters Patent.

Patented July 2, 1918.

Application filed July 21, 1916, Serial No. 110,507. Renewed December 5, 1917. Serial No. 205,683.

To all whom it may concern:

Be it known that I, HARRY G. HALL, a citizen of the United States, residing at Atlanta, in the county of Fulton and State 5 of Georgia, have invented new and useful Improvements in Pasteboard Trays, of which the following is a specification.

This invention has relation, generally, to receptacles of cardboard, or other suitable 10 material, but it more specifically comprehends a tray construction effected from a blank cut and scored in a predetermined manner.

The fundamental object of this invention 15 resides in providing a container, tray-like in contour and formed from a blank so scored and cut when its several sections have been normally positioned, the ordinarily considered weak factors in box construction will 20 be reinforced and thoroughly protected, so as to remain intact under the most adverse circumstances.

Another and further object of this invention is to design a novel form of tray, capable 25 of functioning as a container for such substances as butter, lard, or articles of food associated with a preserving liquid which would be detrimental to the life of the commonly constructed cardboard receptacle.

Another and still further object of this invention is to provide a tray formed from a blank embracing a multiplicity of sections which may be expeditiously and conveniently brought to and locked in proper position, with a minimum expenditure of time 35 and labor.

Further objects of this invention are to provide a tray-like container having the upper edges of its side sections formed with 40 a combination locking and reinforcing flap, to materially increase the strength of the box, and effect a more secure holding together of the parts; and finally, a receptacle having certain hereinafter mentioned structural characteristics and features, by virtue 45 of which improved and beneficial results are accomplished.

Briefly stated, this invention comprises a cardboard blank cut and creased to produce 50 a plurality of sections, namely, bottom, end and side sections, the latter being provided at their upper edges with outwardly and downwardly foldable locking and reinforcing flaps, adapted to overlie and engage certain locking members carried by the end 55 sections, which latter are situated with their

upper edges coincident with those of the side sections when the box is properly folded, whereupon said sections may be securely maintained in proper folded relation. 60

In the accompanying drawings, in which corresponding parts are indicated by similar reference characters:—

Figure 1 is a plan view of the blank illustrating the arrangement of score lines and 65 manner of cutting;

Fig. 2 is a top-plan view of the blank partially folded;

Fig. 3 is a similar view partly in section, and showing all sections in folded position 70 with exception of locking flaps;

Fig. 4 is a top-plan view of the blank, with sections partially assembled, and illustrating the folding of one corner and the position of its extension, prior to bringing 75 said corner and extension to position shown in Fig. 5;

Fig. 5 is a side elevation of the completely assembled blank, with locking flap in position to be folded into engagement 80 with the corner extensions; and

Fig. 6 is a perspective view of the completed tray.

In the manufacture of a cardboard receptacle from a blank, it is absolutely essential, 85 in order to satisfy the rigid service requirements, that interlocking of the assembled sections be such as to eliminate any possibility of a sudden and unexpected collapse, consequently, to meet this requisite, it is 90 necessary to effectively reinforce all exposed parts, such as corners, edges, etc., and also unite the sections of the blank in a manner to make accidental disengagement of the interlocked parts impossible, and it is to 95 this end that I have designed the tray constituting the subject matter of this invention.

In the illustrated embodiment characterizing this invention, there is shown a tray-like receptacle formed from a blank developed in accordance with Fig. 1. The central portion 1 of the blank, within the confines of scores 1^b, constitutes the bottom of the tray. Adjoining bottom section 1, but 100 separated from it by scores 1^b, are the end sections 2, the width of which should correspond to the desired depth of the container. Each end section 2 is provided with an angularly shaped off-setting wing 3, the 110 outlines of which are defined by scores 2^a and 3^a. Also adjacent bottom section 1, and

divided therefrom by scores 1^a, are side sections 4, whose widths correspond to that of end sections 2. These sections 4 are formed on their upper edges with locking flaps 5, the purpose of which will be hereinafter described.

Within the angle set forth by the lateral edges of side sections 4 and scores 3^a of wings 3, are the reinforcing sectionally 10 formed corners 6, the respective sections thereof being designated 7 and 8, and divided from one another by scores 7^a. Carried by the corners 6 and extending laterally therefrom with their extremities coincident 15 with the upper edge of flap 5, when the blank is in a developed state as shown in Fig. 1, are the locking members 9, the combined length of which, when operatively disposed, is equal to the width of end sections 4. 20 As the locking members 9, to be effective, must necessarily, to a certain extent, be separate from the corner sections, the latter are cut on the line 8^a, as clearly shown in Fig. 1.

After the blank is cut and creased as above 25 described, to dispose the several sections in suitable relation, the side sections are folded on scores 1^a, until in a plane substantially at right angles to bottom section 1. In the meantime, as side sections 4 are brought to 30 the aforesaid position, the sections 8 of the reinforcing corners 6 will assume the position shown in Fig. 2, in other words, said sections 8 will be angularly disposed with respect to sections 7; having positioned the 35 side sections, end sections 2 are next folded inwardly on scores 1^b to an extent sufficient to bring scores 3^a of the corner sections contiguous scores 4^a of the side sections. During this operation, the inner surfaces of sections 7 will be disposed in superposed relation with respect to the inner surfaces of 40 sections 8, preparatory to folding into reinforcing position. Then said reinforcing-corners, embracing sections 7 and 8, are 45 folded on scores 3^a, in order to bring the outer surface of sections 8 into engagement with those of said sections 7. When in this position, the locking members 9, carried by the respective reinforcing corners, will extend longitudinal of the side sections and 50 exterior thereof, with their upper edges in alinement with said side sections, as clearly shown in Fig. 5.

Having now assembled the several sections, to lock the same, locking flaps 5 are outwardly and downwardly folded on scores 4^b, which brings their outer surfaces in engagement with those of locking members 9, as shown in Fig. 6. For the purpose of securing locking flap 9 in operative position, 55 staples 10, wire stitches, or other suitable fastening elements may be employed.

Arranging and locking the assembled sections as outlined effects an extremely durable construction, as it affords a reinforce-

ment to all vulnerable points. Ordinarily the side sections are subject to more or less strain, especially in the vicinity of their lateral edges, consequently, by providing the reinforcing corners, an additional 70 double thickness of material is provided at these points, which materially strengthens said side sections, and disposes the aforesaid lateral edges thereof interior of the tray. The locking flap, extending from the locking member, not only securely retains the latter in position, making accidental disengagement of the several sections impossible, but also provides an additional thickness of material at and contiguous the upper edges 75 of said side sections, which is usually exposed, and a weak factor in box construction. 80

In view of the above, it will be obvious that I have designed a tray constructed from a blank, having all parts which ordinarily 85 would be subject to the greater strain reinforced, and one which, by virtue of the reinforcing corner construction, is capable of serving as a container of liquids, without 90 possibility of the latter escaping.

Having now described my invention, what I claim is:—

1. In a receptacle formed from a one piece blank, the combination with a bottom section and upwardly foldable side and end sections, of off-setting wings carried by said end sections, the outer lateral edges of said wings being adapted to register with those of said side sections, corner portions situated intermediate the lateral edges of said wings and side sections, said portions being formed in sections conjointly foldable exterior of the side sections, locking members carried by said corner portions and adapted to extend longitudinal of the side 100 sections, and locking flaps formed on the upper edges of said side sections, said flaps being downwardly foldable into engagement with said locking members, substantially as and for the purpose set forth. 110

2. In a receptacle formed from a one piece blank, the combination with a bottom section and side and end sections folded upwardly therefrom; of a sectional corner portion intermediate the lateral edges of said side and end sections, the sections of said corner portion being conjointly foldable exterior of the side sections, locking members carried by said corner portions and adapted to extend longitudinal of the side 120 sections, and locking flaps formed on the upper edges of said side sections, said flaps being downwardly foldable into engagement with said locking members, substantially as and for the purpose set forth. 115

3. In a receptacle formed from a one piece blank, the combination with a bottom section, and upwardly foldable side and end sections; of offsetting wings carried by said end sections, the outer lateral edges of said 125

wings being adapted to abut those of said side sections, corner portions situated intermediate the lateral edges of said wings and side sections, said portions being formed in sections conjointly foldable exterior of the side sections, and interlocking means in connection with said side sections and corner portions, substantially as and for the purpose set forth.

10 4. In a receptacle formed from a one piece blank, the combination with a bottom section and upwardly foldable side and end sections; of offsetting wings carried by said end sections, corner portions situated intermediate the lateral edges of said wings and

side sections, said portions being formed in sections conjointly foldable exterior of the side sections, locking members carried by said corner portions and adapted to extend longitudinal of the side sections, and locking flaps formed on the upper edges of said side sections, said flaps being downwardly foldable into engagement with said locking members, substantially as and for the purpose set forth.
